UNITED STATES PATENT OFFICE.

MICHAEL HEARN, OF HAMPSTEAD, ENGLAND.

TYPE-WRITING MACHINE.

SPECIFICATION forming part of Letters Patent No. 453,241, dated June 2, 1891.

Application filed June 12, 1888. Serial No. 276,884. (No model.) Patented in England December 8, 1886, No. 16,068.

To all whom it may concern:

Be it known that I, MICHAEL HEARN, a subject of Victoria, Queen of Great Britain and Ireland, residing at 17 Nassington Road, 5 Hampstead, in the county of Middlesex, England, have invented a new and useful Type-Writing Machine, (for which I have obtained a patent in Great Britain, No. 16,068, bearing date December 8, 1886,) of which the following is a specification.

My invention relates to improvements in type-writing machines in which weighted or balanced type-levers are operated by finger-keys; and the objects of my invention are to 15 provide an improved finger-key machine simple in construction and moderate as to price. I attain these objects by mechanism illustrated in the accompanying drawings, in which—

20 Figure 1 is a part sectional view of the entire machine on the line 1 2, Fig. 2; Fig. 2, a top view of so much of the machine as is necessary to illustrate the mechanism, the other half being in all respects exactly the same. 25 Fig. 3 is a perspective view of a portion of the mechanism. Fig. 4 is a cross-section on line 4 4 of Fig. 1. Fig. 5 is a top view of the case which fits over the machine.

Similar letters and figures refer to similar 30 parts throughout the several views.

The table or frame A, Figs. 1 and 2, may be a skeleton frame of metal or one entire piece of wood, having a metal bed, where the bracket B is fixed and the rollers of the 35 per-carriage run. To this table a semicircular bracket B is secured, and on this bracket the semicircular plates C D, hereinafter called "guide-plates," are secured by means of screws. The guide-plates are fitted one over 40 the other, as shown in the perspective view, Fig. 4, the said guide-plates having radial slots a a a, Fig. 2, and the lower plate D having a groove b b b, which intersects the said radial slots a a. In these radial slots the 45 type-levers E, Fig. 1, are fitted and rotate on a wire bearing fitting into the said intersecting groove b. The lower ends of the type-levers E are enlarged, and thereby weighted, so that their upper ends, which carry the type, are 50 held normally vertical, as shown in Fig. 1. Such enlarged and weighted portions are

rounded corresponding to recesses in the inner ends of the finger-keys F. It is obvious that on tapping finger-keys F the type-levers E are rapidly impelled to the printing-point. 55 At the same time the keys F rapidly depress lever L, which operates the spacing-lever H.

In order to take up wear in the radial slots, a bevel-headed screw Z, Figs. 1 and 4, is fitted into the backs of the type-levers E, and is 60 screwed farther down when necessary.

The finger-keys F, Fig. 1, are similarly fitted into a plate G, Figs. 1 and 2, having radial slots c c and a groove d d, the wire bearing on which the finger-keys are pivoted being kept in position by flange-headed screws e, Figs. 1 and 2.

The spacing movement is effected by a lever H, Fig. 1, pivoted at f, and operating two racks g h by means of a beveled tooth i, Figs. 70 2 and 3. A spiral spring I draws the carriage from right to left, and a spring J, attached to an arm K, retracts the lever H, which is directly operated on by the circular lever L, Fig. 1. Ribbon-spools M are fitted to supports N, hinged at 7, Figs. 1 and 2, to a piece 75 8, fixed in the lower guide-plate D. A bent rod o, Fig. 2, connects supports N, and is used to run back the spools, in order to examine the type-writing as it progresses. Said spools 80 are operated by jointed levers O, having a cross-piece q, that engages ratchet-wheels P, and attached at one end p, Fig. 5, and to the lever L. A thumb-nut W regulates the movement of the spools. These levers are thrown 85 into and out of gear with their respective ratchet-wheels by a rod r and pin S, Figs. 1 and 2. The roller Q is mounted and slides in supports R, but is kept in position by a rod S.

X is a circular support, on which the characters are engraved.

Z is the spacing-plate. Over all the type-levers and finger-keys a metal cover 3 is fitted, as shown in Fig. 1, and the half plan, Fig. 5. Inside the cover a cushion 4 is fitted, against 95 which the type-levers rest, as shown in Fig. 1. The upper part 5 of the said cover may be made removable, in order to more easily adjust the type-pieces 6 in the type-levers.

It will be seen from the foregoing that the 100 machine is semicircular in form, and that the spacing-lever H is centrally pivoted.

Having now particularly described my invention, what I desire to secure by Letters Patent, is—

In a type-writing machine, the combination, with finger-keys and the slotted guide-
5 plate C, of the type-levers E, having a counterpoise at one end, and a bevel-headed screw

fitted to them, substantially as shown and described.

MICHAEL HEARN.
